UNITED STATES PATENT OFFICE.

FREDERICK OTT, OF ESTRELLA, CALIFORNIA.

CAR-COUPING.

SPECIFICATION forming part of Letters Patent No. 395,072, dated December 25, 1888.

Application filed June 27, 1888. Serial No. 278,344. (No model.)

To all whom it may concern:

Be it known that I, FREDERICK OTT, a citizen of the United States, residing at Estrella, in the county of San Luis Obispo and State 5 of California, have invented a new and useful Improvement in Car-Couplings, of which the following is a specification.

The invention relates to improvements in car-couplers; and it consists in the construction and novel combination of parts herein-after described, illustrated in the accompanying drawings, and pointed out in the claims hereto appended.

Figure 1 of the drawings represents a perspective view of the end of a car with a coupler embodying the invention attached. Fig. 15 2 represents a plan view of one of the draw-heads detached, with the coupling-pin and the frame thereof removed to more clearly 20 show the spring-controlled pin-detent. Fig. 3 represents a central vertical longitudinal section of one of the draw-heads. Fig. 4 represents a face or front view of one of the draw-heads.

25 Referring to the drawings by letter, A designates the end of a car having the draw-bar, to which the recessed draw-head B is attached in the usual manner.

C is a frame standing vertically from the 30 draw-head, near the outer end thereof, and composed of the side arms, c c , and the transverse bearing-bars c' c^2 , respectively, which connect the said arms above the draw-head.

D is the coupling-pin, which is much longer 35 than in the ordinary style of coupler, and which passes down through the bearings in the bars c' c^2 and into the pin-openings d in the roof and floor of the draw-head. The inner edges of the arms c enter the vertical grooves d' in the 40 sides of the draw-head, and the lower ends of said arms are reduced and shouldered, as at d^2 , the slotted bar d^3 being secured on said ends by the pins d^4 , that pass through suitable openings in said bar. The frame C 45 thus has its lower bearing-bar, c^2 , on top of the draw-head, and its connecting-bar d^3 below the same. The coupling-pin passes up centrally through the space E, between the bearing-bars c' c^2 , and has passed through a 50 longitudinal slot, at a proper point in its length, the stop e, which, by bearing on the bars c' c^2 , prevent the coupling-pin from be-

coming detached, either upward or downward.

e' is an opening through the coupling-pin, 55 and e^2 is a pin that can be passed through said opening above the upper bearing-bar, c' , the said pin being connected to the frame C by a cord, e^3 .

F is a detent-plate having the similar transverse arms f lying upon the upper surface of the draw-head, which arms are bent downward over the sides thereof, where they have the lateral frontward projections, f' , provided with the vertical buffer end plates, f^2 . The said 60 projections f' pass through the notches f^3 on the inner edges of the arms c . The said plate has a forwardly-standing arm, G, that passes under the point of the coupling-pin D when the same is raised, and a rearwardly-standing arm, H, provided with a longitudinal slot, h , through which the T-shaped pin or bolt I passes, the lateral projections of which overlie the said arm H and hold the detent-plate down on the draw-head. The rear end of the arm 65 H is bent upward and connected to the lower bearing-bar, c^2 , by the coiled spring i, which forces the detent-arm G under the point of the coupling-pin when the latter is raised.

J is the link having the central double bend, 70 j , by means of which draw-heads of unequal height may be coupled. The said bend permits the ends of the link to stand parallel to each other at different elevations.

K is a spring-rod, with its rear end secured 75 to the outer surface of the floor of the draw-head and with its front portion bent upward through an opening, k , in the draw-head in rear of the lower pin-opening, and formed within the draw-head into a rearwardly-projecting hook, k' , which engages over the end of the link within the draw-head and holds the link in position to engage.

If desired, a perfectly straight link may be 80 substituted for the link bent as described.

When the brakeman on top of the car lifts the coupling-pin, the detent-arm G is forced thereunder by the coiled spring i, and the pin is thereby upheld till the buffer-plates f^2 of the opposing draw-heads strike together, driving back the detent-plate against the action of the spring i and permitting the coupling-pin to fall. When the buffer-plates are driven 85 completely inward, they enter recesses in the 90

end of the draw-head and are thereby prevented from breakage.

By means of the pin e^2 and opening e' the coupling-pin can be held up and not allowed 5 to engage the link.

Having described my invention, I claim—

1. The combination of the draw-head having an opening, k , in its bottom, and the spring K, passing through the opening k and having one end permanently secured to the under side of the draw-head and its other end bent rearward to form the hook k' , as specified.
2. The combination of the draw-head, the frame C, secured thereto, the coupling-pin mounted in said frame, the slotted detent-plate arranged on the upper side of the draw-head and adapted to support the coupling-pin, the securing-stud passed through the slot in said plate into the draw-head, and the spring 5 having its opposite ends secured, respectively, to the frame C and the detent-plate, as set forth.

3. The combination, with the draw-head, the vertical frame, and the coupling-pin, of the detent-plate having the detent-arm G and 25 the slotted arm H, the pin or bolt I, the coiled spring i, and the buffer-plates f^2 on the lateral extensions of the detent-plate, substantially as specified.

4. In a car-coupler, the combination, with 30 the recessed draw-head and the link, of the spring-rod K, having the rearwardly-standing hook k' on its end within the draw-head, substantially as specified.

In testimony that I claim the foregoing as 35 my own I have hereto affixed my signature in presence of two witnesses.

FREDERICK OTT.
